DESIGN FOR A SLIPPER

Robert Mintz, New York, N. Y.

Application August 30, 1943, Serial No. 111,029

Term of patent 7 years

To all whom it may concern:

Be it known that I, Robert Mintz, a citizen of the United States, residing in New York city, in the county of New York and State of New York, have invented a new, original, and ornamental Design for a Slipper, of which the following is a specification, reference being had to the accompanying drawing, forming part thereof.

Fig. 1 is a side elevational view of a slipper with the top turned up, showing my new design.

Fig. 2 is a side elevational view of the slipper shown in Fig. 1 but with the upper portion turned downwardly; and

Fig. 3 is a fragmentary plan view of the toe portion of the slipper illustrating more clearly the details of that part of the slipper.

My design for a slipper, which presents substantially the same appearance from both sides, is characterized by the very pronounced outstanding bead surrounding the edges of the entire sole and extending upwardly over the center of the vamp and the heel of the slipper, as shown.

I claim:

The ornamental design for a slipper, substantially as shown and described.

ROBERT MINTZ.
